COMBINATION TOOL

Application filed June 29, 1925. Serial No. 40,342.

The object of my invention is to provide a handy calculating tool and computing instrument which is especially adapted for a carpenter's or a builder's use. My improved tool is arranged to indicate the required cuts for rafters and for stairs and for various other similar uses.

A further object of my invention is to provide a combination tool of this character which is extremely sturdy and which may be adjusted very closely and yet one which can be folded compactly into a very small space, which when folded may be conveniently carried about. All other tools of this character with which I am familiar, cannot be conveniently carried about, and thus are usually left in the tool kit and thus are not used as often as they might be for the reason that the carpenter or builder must leave the place where he is working, go to his tool-kit and return with the device before he can use the same. Often, rather than do this, he will calculate the desired angle or length rather than take the time to procure the instrument.

I attain these and other objects by means of an instrument comprising a straight-edge formed on one of its edges with oppositely projecting flanges normal to the said straight edge, and two arms each pivoted at one end to the straight-edge at a common point, one of said arms being provided with a slidable extension, said arms being correspondingly graduated, and the ends of said arms adjacent said common pivotal point being provided with a notch, respectively, said notches arranged to register when said arms are arranged normally to each other, a locking-pin movable on said straight-edge, adapted to be inserted in said notches when placed in registration, and braces pivotally connected at one end to each of said arms, the opposite ends of said braces being movably connected to the straight-edge and graduations provided for each of said movable ends of said braces.

The further details of construction and mode of operation of this device are herein-after described with reference to the accompanying drawings, in which:

Fig. 1 is an elevation of my improved tool with the arms shown fully extended;

Fig. 2 is a plan view of said tool with the arms withdrawn within the body;

Fig. 3 is an elevation of said tool with said arms withdrawn into said body so as to be entirely housed therein, portions of said body being shown broken away to disclose details of construction;

Fig. 4 is a larger scaled transverse section through said body which is pivotally connected with one of said brace arms, said section being taken on the line 4-4 of Fig. 1;

Fig. 5 is an enlarged fragmentary elevation of said pivotal connection;

Fig. 6 is a larger scaled view of the indicator carried by said pivotal connection;

Fig. 7 is a similar scaled fragmentary elevation of the pivotal connection with said body and the other brace arm;

Fig. 8 is a fragmentary elevation of my tool with the arms shown extended relatively to each other so as to constitute a space divider, portions of the body being broken away to disclose details of construction;

Fig. 9 is a larger scaled longitudinal section of one of said arms taken on the line 9-9 of Fig. 8, showing details of construction which permit said arms to be longitudinally extended;

Figs. 10 and 11 are foreshortened perspective views of the arms of my device;

Fig. 12 is an elevation of my improved tool with one arm supported and with the body shown as broken away, said figure showing said devices engaging said arms with each other so that they are arranged at right angles; and

Fig. 13 is a section taken on the line 13-13 of Fig. 12.

My tool comprises a straight edge *a* in which are arms *b* and *c* pivoted at a common point. A brace *d* is pivotally connected at one of its ends *d'* to the ear *b'* formed on the arm *b* and is slidably fastened at its other end *d''* to the body *a* through the slot *e*. A tightening nut *f* is provided on the pin *f'* by which said connection is made so that the brace can be held in set position by tightening said nut. A second brace *g* is pivotally

supported at its end g' to the ear c' formed on the arm c and is slidably connected at its opposite end to the body a through the slot h . In this brace also a lock nut i is provided on a pin i' which slides into said slot h , said nut being provided to hold the arm in set position in the slot. Said slots e and h have no definite form, but are merely arranged to permit the arms b and c to fold within the body a and the scales at each side thereof have been marked on the body when the arms have been set to the desired angle. In other words, the slots and scales are not computed so that the arms will make definite angles with each other or with the body, but are marked to correspond with said arms when said arms have been set at the various angles. The body is preferably made of a single sheet of metal which is folded longitudinally upon its center line, as shown in Fig. 4 and spaced sufficiently to receive the arms b and c when folded into the said straight edge, and the upper edges are arranged with outwardly extending flanges a^4 and a^5 which form a right angle with said sides a' and a^2 , respectively. The ends are partially closed, as shown in Figs. 2 and 3, space being provided for the arms b and c to extend slightly beyond said ends, as shown in Fig. 3, so that they can be grasped when said arms are folded into said body. Indicators j and m are carried by the pins f' and i' , respectively. The indicator j is adapted to register with the scale l alongside the slot e and the indicator m is adapted to register with the scales n or n' at each side of the slot h . For this purpose, the indicator m is provided with two points, one of which is adapted to register with the scale n and the other with the scale n' . The indicators are provided with formed sliding portions which fit exactly into the slots and thus prevent said indicators from rotating about their pins. Thus, for example, the indicator j , shown in Fig. 6, is provided with a shouldered portion j' which is adapted to fit in the slot e and the indicator m is provided with a shouldered portion m' adapted to fit in the slot h . The arms b and c are pivoted upon a pin o extending through the straight-edge, said member being a relatively fixed pivot. The arm b at the pivoted end is made of a single thickness of material and the arm c of two thicknesses spaced apart at its pivoted end thus permitting the arm b to be mounted within the arm c , as is indicated in Figs. 10 and 11. The arm b is longitudinally extensible, being provided with a head portion b^2 of one thickness of material. The arm b' is provided with a slot b^3 and said head portion is provided with a locking device b^4 which extends through said slot. The locking device is longitudinally slidable in the head b^2 and is provided with two beveled gripping points b^5 .

provided with two turned flanges b^6 which are adapted to be engaged by said points b^5 and are adapted to be moved towards each other so as to clamp the arm b between them in a desired position in the slot b^3 . Said clamping action tends to clamp the part b^6 over the blade and thus holds the head b^2 in set position. The arm c is made up, as before mentioned, of two members c^2 which are spaced apart and between which the blade c^3 is fixed.

The slideable head b^2 of the arm b carries a scale p and the blade c^3 of the arm c is provided with a corresponding scale q . The ends of said arms b and c below the pivot o are provided with notches b^7 and c^4 , respectively. Said notches are arranged so that they extend an equal distance from the pivot o and are substantially radial relative thereto. Said notches move over a slot r which has a portion r' concentric to the pivot point o . The remainder r^2 of said slot is at substantially right angles to said portion r' . A button s is slideably mounted in said slot r and is provided with heads s' at each side of the body a to prevent said button from being removed from said slot. If it is desired to move the arms b and c independently of each other, the button is arranged so as to lie within the portion r^2 of the slot, but if it is desired to lock said arms relative to each other at right angles, the arms are adjusted so that the notches c^4 and b^7 coincide with the portion r^2 . The button is then pushed into said notches and in this position the arms are locked so that they are held against relative movement with each other.

My combination tool as before mentioned has a number of uses, the details of the application of which I will now explain.

As a space divider, any space may be divided with my combination tool into a desired number of equal parts, within the scope of the graduations on the arms b and c . The arm b is longitudinally extended and the space to be divided is reduced to a scale of one foot to one inch and laid off between the sides of the angle formed by the said arms at the opposite numbers 12, on the scales p and q .

The number of divisions desired is then measured directly in inches between the arms b and c at the number of the scales p and q corresponding to the number of desired divisions.

For example, if 12 feet is to be divided into twenty-four equal parts, the arms b , c are adjusted until the space between them, at the numbers 12 on each scale p , q will be twelve inches and then the space between the arms at the numbers 24 on the said scale is measured, which will be six inches, the dimension of each division. By reference to the geometrical theorem that, "similar triangles are to each other as the ratios of their corre-

sponding sides", the truth of this conclusion will be readily understood.

As a rafter miter the arms *b* and *c* are set at right angles by the bolt *s* as before mentioned and for determining the cuts of jack and common rafters the arm *c* and the main member will indicate the side and plumb cut. The indicator *i* is set at the desired pitch on the scale *n* as for instance an 8-12 pitch, the indicator will be set at 8 and similarly for other pitches.

For the side cuts for hip or valley rafters the arm *b* will be set by the indicator *j* on the scale *l* for the desired pitch as in the case above, and the side cut will be indicated by the arm *b* and the brace *d*.

The plumb cut for hip and valley rafters will be indicated by the arm *b* and the main member.

The side and plumb cuts for cripple rafters are indicated by the brace *g* and the arm *c*, the pitch of the roof being set as before mentioned on the scale *n*.

The scale *n'* on the groove *h* is provided to give the miter cuts for the sheeting of a roof, the cuts being determined by the angle formed by the arm *c* and the main member *a*.

As a bevel square and try square, one arm may be folded away, and the other set for the desired bevel or right angle or both arms *b* and *c* may be clamped for the desired angle by the braces *d* and *g*, and the thumb nuts *f* and *i*.

The actual number of uses to which my combination tool may be set is only limited by the number of conditions which a builder may encounter in the course of his work. As for instance, my tool may be used to lay off the miters for a regular polygon of any number of sides, it only being necessary for the builder to know the ratio or pitch of any two adjacent sides.

I claim:

1. An instrument of the character described, comprising a straight-edge formed on one of its edges with oppositely projecting flanges normal to the said straight-edge, two arms each pivoted adjacent one end to the straight edge between the flanges at a common point, one of said arms being provided with a sliding extension, said arms being correspondingly graduated, and means, carried by the straight-edge, adapted to lock said arms together when arranged normal to each other.

2. An instrument of the character described, comprising a straight-edge formed on one of its edges with oppositely projecting flanges normal to the said straight-edge, two arms each pivoted adjacent one end to the straight edge between the flanges at a common point, the ends of said arms adjacent said common pivotal point being provided with a notch, respectively, said notches being arranged to register when said arms are ar-

ranged normally to each other, a locking-pin movable on said straight-edge, and adapted to be inserted in said notches when placed in registration.

3. An instrument of the character described, comprising a straight edge formed from a sheet of folded metal, said straight edge being U-shaped in cross section and the edges of the walls being formed with oppositely projecting flanges normal to said straight edge, two arms pivoted adjacent their ends between the walls of the straight edge at a common point, means carried by the straight edge adapted to lock said arms together when arranged normal to each other, so and the space between the walls of the straight edge forming a recess adapted to receive either arm when the other is arranged normal to the straight edge and braces pivotally connected at one end to said arms respectively, and slidably connected at their other ends to said straight edge.
